MOP HOLDER HAVING A HOLLOW HANDLE AND A RETRACTABLE JAW

Filed March 29, 1950

UNITED STATES PATENT OFFICE

2,594,392

MOP HOLDER HAVING A HOLLOW HANDLE
AND A RETRACTABLE JAWSamuel J. Care, Forty-Fort, and Andrew Shara,
Kingston, Pa.

Application March 29, 1950, Serial No. 152,608

6 Claims. (Cl. 15—153)

1

This invention relates to a mop and has for an object to provide an improved mop holder and handle which is extremely rugged and of great durability and which will hold the mop-head firmly and securely while in use, yet will release it readily for easy replacement.

A further object of this invention is to provide a mop handle of hollow metal and hence great strength with means at the upper end of the handle for controlling the fastening and releasing of the mop head at the other end.

Still a further object of this invention is to provide a remotely controlled mophead fastening means which is adjustable according to the thickness of the mop whereby a heavy or light mophead may be secured with equal facility.

A further object of this invention is to provide an extendable disappearing mop suspending means in combination with the mop securing knob.

With the foregoing and other objects in view, as will hereinafter become apparent, this invention provides a construction, combination and arrangement of parts hereinafter set forth, claimed and disclosed in the accompanying drawing, wherein

Fig. 1 is an elevational view of the mop in mop securing position;

Fig. 2 is a side view of Fig. 1;

Fig. 3 is a sectional view through the mop handle with the mop holding means in mop releasing position;

Fig. 4 is an elevational view similar to Fig. 1;

Fig. 5 is a sectional view through the mop tightening knob; and

Fig. 6 is a fragmentary view of a modified form of connecting rod within the mop.

There is shown at 10 the mop of this invention consisting of a hollow metal tube 11 having its mophead end 12 flattened somewhat into a triangular shape and provided with flared lips 13 while the other end of the tube 11 has a short longitudinally extending slot 16 connecting with a radial slot 17 in the otherwise closed end. Arranged to extend within the hollow tube 11 and the flattened triangular end 12 is a mophead holding means consisting of a triangular-shaped rod 14 whose apex sides are joined at 15 and then extend at 18 through the hollow metal tube to a point 20 intermediate the ends of the longitudinal slot 16. These extending sides 18 may be soldered or welded together at both points 15 and 20 and, if desired, at several intermediate points.

Adjacent point 20 there is pivoted one end 21

2

of a threaded stud 22 whose other end is arranged to be threaded into an operating knob 23. If the knob 23 is of metal, the threads 24 for the stud 22 may be cut therein, but if the knob 23 is of wood or plastic, suitable threads may be provided therewithin. The closed end of knob 23 is preferably rounded while the diameter of the knob 23 is substantially equal at its open end to the diameter of the tube 11. Extending longitudinally through the knob 23 are a pair of counterbores 25 cooperating with an extendable mop supporting U-shaped bail 26 whose legs are peaned over or otherwise provided with permanent or attachable enlargements at 27 movable within the large bore of the counterbore 25 thereby preventing the U-shaped bail 26 from being completely withdrawn therefrom. In the opposite direction bight 28 of the U-shaped bail 26 may countersink within a slot 30 in the end of the knob 23, the slot 30 having a fingernail kerf 31 at one side thereof permitting access thereto for withdrawing the U-shaped bail 26. In the withdrawing position this U-shaped bail 26 is intended to cooperate with a nail or hook for suspending or supporting the mop 10 in a convenient position.

Instead of the apex sides of the triangle extending at 18 a hollow or solid rod 35 may be provided having a bifurcated end 36 and transverse apertures 37 for pivotally attaching it to the end 21 of the threaded stud 22, the other end of the rod 35 being welded or soldered to the triangle 14 at its apex point 15. The mop 10 with the rod 35 substituted for the extended sides 18 would be somewhat stronger and is particularly intended for use where extreme ruggedness is desirable as in office or factory cleaning.

In operation, the mophead 40 is placed about base member 19 of triangle 14 while in the position shown in Figs. 3 and 4. To secure mophead 40 in operative position, the knob 23 is then moved to withdraw the triangle 14 into the mop handle end 12 until the knob 23 can be pivoted about from the position shown in Figs. 3 and 4 to the position shown in Figs. 1 and 2. The knob 23 is then rotated drawing the threaded stud 22 therein until the mophead 40 is tightly caught and held between the triangle base 19 and the lips 13 of flattened mop end 12 while simultaneously the knob 23 becomes tight against the closed end 17 of mop tube 11. To release and replace the mophead 40, the knob 23 is threaded in the opposite direction to relieve the pressure thereon until it can be pivoted over the closed end 17 to the position shown in Figs. 3

and 4 permitting the mophead to be removed and replaced. When not in use, the mop 10 may be supported on any convenient hook by first withdrawing the supporting U 26 from the knob 23.

While the preferred form of this invention has been shown and described, it will be understood that this invention is not restricted to the particular details of construction and arrangement hereinbefore set forth but that changes in such detail of construction may be made within the scope of what is hereinafter claimed.

Having thus set forth and disclosed the nature of this invention, what is claimed is:

1. A mop comprising a hollow metal tube providing a mop handle, said tube being closed at one end but having a radial slot therein connecting to a short longitudinal slot, the other end of said hollow metal tube being flattened and enlarged to substantially triangular outline open at its end and provided with flaring lips, a triangular mophead holder having a transverse aperture arranged to extend from and be retracted into said open triangular end of said mop handle, means extending from the apex of said triangular mophead holder and through said hollow metal tube to a point adjacent said longitudinal slot therein, a threaded stud pivotally secured to the end of said means adjacent said longitudinal slot, and a knob adjustably threaded to said threaded stud externally of said hollow tube and having a diameter at least equal to the diameter of said hollow tube.

2. A mop comprising a hollow metal tube providing a mop handle, said tube being closed at one end but having a radial slot therein connecting to a short longitudinal slot, the other end of said hollow metal tube being flattened and enlarged to substantially triangular outline open at its end and provided with flaring lips, a triangular mophead holder having a transverse aperture arranged to extend from and be retracted into said open triangular end of said mop handle, means extending from the apex of said triangular mophead holder and through said hollow metal tube to a point adjacent said longitudinal slot therein, a threaded stud pivotally secured to the end of said means adjacent said longitudinal slot, a knob adjustably threaded to said threaded stud externally of said hollow tube and having a diameter at least equal to the diameter of said hollow tube, said knob being provided with a pair of spaced apart axially aligned large and small bores providing shoulders therebetween and an extendable mop suspending U-shaped bail having its legs retractable and extendable through said axially aligned bores, the ends of said legs being provided with enlargements within said large bores and arranged to abut said shoulders to limit the extension of said U-shaped bail.

3. A mop comprising a hollow metal tube providing a mop handle, said tube being closed at one end but having a radial slot therein connecting to a short longitudinal slot, the other end of said hollow metal tube being flattened and enlarged to substantially triangular outline open at its end and provided with flaring lips, a triangular mophead holder having a transverse aperture arranged to extend from and be retracted into said open triangular end of said mop handle, means extending from the apex of said triangular mophead holder and through said hollow metal tube to a point adjacent said longitudinal slot therein, a threaded stud pivotally secured to the end of said means adjacent said longitudinal

slot, a knob adjustably threaded to said threaded stud externally of said hollow tube and having a diameter at least equal to the diameter of said hollow tube, said knob being provided with a pair of spaced apart axially aligned large and small bores providing shoulders therebetween and an extendable mop suspending U-shaped bail having its legs retractable and extendable through said axially aligned bores, the ends of said legs being provided with enlargements within said large bores and arranged to abut said shoulders to limit the extension of said U-shaped bail, the end of said knob being kerf slotted to retractably countersink said U.

4. A mop comprising a hollow metal tube providing a mop handle, said tube being closed at one end but having a radial slot therein connecting to a short longitudinal slot, the other end of said hollow metal tube being flattened and enlarged to substantially triangular outline open at its end and provided with flaring lips, a triangular mophead holder having a transverse aperture arranged to extend from and be retracted into said open triangular end of said mop handle, means extending from the apex of said triangular mophead holder and through said hollow metal tube to a point adjacent said longitudinal slot therein, said means comprising integrally extending parallel portions of said apex sides secured together, a threaded stud pivotally secured to the end of said means adjacent said longitudinal slot, and a knob adjustably threaded to said threaded stud externally of said hollow tube and having a diameter at least equal to the diameter of said hollow tube.

5. A mop comprising a hollow metal tube providing a mop handle, said tube being closed at one end but having a radial slot therein connecting to a short longitudinal slot, the other end of said hollow metal tube being flattened and enlarged to substantially triangular outline open at its end and provided with flaring lips, a triangular mophead holder having a transverse aperture arranged to extend from and be retracted into said open triangular end of said mop handle, means extending from the apex of said triangular mophead holder and through said hollow metal tube to a point adjacent said longitudinal slot therein, said means comprising a rod extending from said triangular mophead holder adjacent its apex, a threaded stud pivotally secured to the end of said means adjacent said longitudinal slot, and a knob adjustably threaded to said threaded stud externally of said hollow tube and having a diameter at least equal to the diameter of said hollow tube.

6. A mop comprising a hollow metal tube providing a mop handle, said tube being closed at one end but having a radial slot therein connecting to a short longitudinal slot, the other end of said hollow metal tube being flattened and enlarged to substantially triangular outline open at its end and provided with flaring lips, a triangular mophead holder having a transverse aperture arranged to extend from and be retracted into said open triangular end of said mop handle, means extending from the apex of said triangular mophead holder and through said hollow metal tube to a point adjacent said longitudinal slot therein, said means comprising a rod extending from said triangular mophead holder adjacent its apex, said rod being hollow, a threaded stud pivotally secured to the end of said means adjacent said longitudinal slot, and a knob adjustably threaded to said threaded stud externally

2,594,392

5

of said hollow tube and having a diameter at least equal to the diameter of said hollow tube.
